CLAIM

The ornamental design for a jug coozie, as shown and described.

DESCRIPTION

FIG. 1: Is a perspective view of the jug coozie shown with flap closed;

FIG. 2: Is a side view of the jug coozie;

FIG. 3: Is a front view of the jug coozie;

FIG. 4: Is a top view of the jug coozie;

FIG. 5: Is a side view of the jug coozie;

FIG. 6: Is a rear view of the jug coozie;

FIG. 7 is a bottom view of the jug coozie; and,

FIG. 8 is a perspective view of the jug coozie showing with the flap open.

The broken lines shown in the drawings illustrate portions of the jug coozie that form no part of the claimed design.
